CUPHOLDER ATTACHMENT

Kenneth H. MacKay, Ocala, Fla.

Application November 24, 1952, Serial No. 22,424

Term of patent 14 years

(Cl. D80—7)

To all whom it may concern:

Be it known that I, Kenneth H. MacKay, a citizen of the United States, residing at Ocala, in the county of Marion and State of Florida, have invented a new, original, and ornamental Design for a Cupholder Attachment, of which the following is a specification, reference being had to the accompanying drawing, forming a part thereof.

Fig. 1 is a front elevational view of a cupholder attachment, showing my new design;

Fig. 2 is a side elevational view;

Fig. 3 is a top plan view; and

Fig. 4 is a front perspective view with the broken lines as shown in Fig. 1 omitted for convenience of illustration.

The essential features of my design are shown in full lines.

I claim:

The ornamental design for a cupholder attachment, as shown and described.

KENNETH H. MACKAY.
